UNITED STATES PATENT OFFICE.

LOUIS GÁBOR KOZMA, OF NEW YORK, N. Y.

PAPER-HANGER'S TOOL.

Application filed June 17, 1926, Serial No. 116,523. Renewed March 15, 1929.

This invention relates to a tool for paper hangers, and more particularly to a safety appliance for paper cutting tools.

In accordance with the present invention I provide a guard applicable to a straight edge ruler, whereby the user's hand will be protected should the knife slip in cutting paper. The guard is so arranged that, when not in use it will not interfere with the use of the ruler as a measuring stick or the like, and that it be applicable to the usual straight edge ruler.

The invention will more clearly appear from the following description of a preferred embodiment of the invention and the appended claims.

In the drawings Fig. 1 illustrates the device in use with guard open; Fig. 2 is a rear view of the device; and Fig. 3 is a side elevation of the guard in closed position.

The guard consists of a base plate 1 which may be suitably fastened by means of screws to a straight edge ruler 2 and a guard plate 3 hinged to the base plate at 4. The guard plate can be opened up to a position substantially at right angles with the base plate and it is held in that position by means of a stop 5. One of the edges of plate 3 is rounded as indicated at 12 so as to avoid tearing of wall paper that may curl up. The stop is hinged to the base plate 1 at 6^a and is adapted to be held in its open position between two embossings 6 in the guard plate 3. When folded down, as shown in Fig. 3, the guard plate is held closed by means of a pivoted hook 7 engaging a suitable embossing 8 in the base plate 1. At one end the base plate 1 is slightly raised, as indicated at 9, and forms a pocket in which a knife, such as indicated by 10, may be kept. A piece of emery paper 11 or the like is fastened to the ruler so as to permit ready sharpening of the knife. When the guard is open the paper hanger applies pressure on the base plate 1 and his hand is protected by the plate 3 should the knife slip. It should be noted that the hinges 4 and 6^a are so arranged that the guard plate 3 and the stop 5 may lie flush against the base plate 1.

This device permits the safe use of the most reliable paper cutting tool, i. e., a simple knife, for use by paper hangers. In order to protect users against injury, various types of scissors and rolling cutters have been devised as cutting tools for paper hangers. However, these devices were unfit because they

slowed down the operation materially, and notwithstanding the almost daily occurrence of accidents that happen with the use of a plain knife, paper hangers have generally adhered to its use. My guard permits the use of a plain knife, fully protects the user against injury without slowing down the cutting operation.

Owing to the presence of the guard 3 the user need not fear injury, not even when pressing against that side of the ruler against which the knife is applied.

What I claim is:

1. In a folding tool for paper hangers, a ruler, a guard attached near one edge thereof, and extending away from the ruler in a plane substantially parallel to the said edge thereof, when the tool is in open operating position, said guard being hinged to the edge of said ruler whereby the guard may be folded down on the ruler, and means for holding said tool in an open operating position comprising a member hinged to said ruler at right angles to said guard.

2. In a tool for paper hangers, a ruler, a hand protecting guard hinged near one edge thereof, means for locking said guard in a folded condition against said ruler, means comprising the edges of the said ruler and guard for preventing said tool from being opened too far and a member hinged to said ruler at right angles to said guard for maintaining said tool in an opened operating condition.

3. In a tool for paper hangers, a ruler, a hand protecting guard hinged near one edge thereof, a lock for holding the guard in a position folded down against the ruler, and a stop hinged to said ruler at right angles to said guard for holding said guard open substantially at right angles to said ruler.

4. In a portable tool for paper hangers, a ruler means attached thereto adapted to protect the hand of the operator from injury by tools drawn along the edge of the ruler, said means comprising a guard in the form of a plate attached to the ruler near the edge thereof and hinges for attaching the guard to the ruler, whereby the guard may be folded flat against the ruler, means comprising a member hinged to said ruler at right angles to said guard for maintaining said guard in an operative position, and means for maintaining said member in proper position to hold said guard in operative position.

5. In a folding tool for paper hangers, a

- ruler, a guard hinged to said ruler, a member hinged to said ruler at right angles to said guard for maintaining said tool in an unfolded condition, a pair of projections on said guard for maintaining said member in an unfolded position and means comprising the hinged edges of said ruler and said guard for preventing said guard from being unfolded past its operative position.
- 5 10 6. A tool for paper hangers comprising a wooden ruler, a plate attached to said ruler, said plate having a deformed portion for holding a paper hanger's knife, a guard

hinged to said plate, a member hinged to said plate at right angles to said guard for 15 maintaining said guard at right angles to said plate, means on the guard for maintaining said member in operative position, and means associated with the said guard for maintaining the guard and member in a 20 folded position.

In testimony whereof, I have signed my name to this specification this 15th day of June, 1926.

LOUIS GÁBOR KOZMA.
